Specification for Design.

Patented May 20, 1919.

Application filed December 28, 1918. Serial No. 268,777. Term of patent 14 years

To all whom it may concern:

Be it known that I, JOHN G. GATES, a citizen of the United States, residing at the city and county of Denver and State of Colorado, have invented a new, original, and ornamental Design for Rubber Tires, of which the following is a specification, reference being had to the accompanying drawing, forming a part thereof.

In this drawing, Figure 1 is a fragmentary perspective view, and Fig. 2 a fragmentary elevation of a rubber tire, showing my new design.

I claim:

The ornamental design for a rubber tire as shown.

In testimony whereof I affix my signature.
JOHN G. GATES.
